US0D1055037S

(12) **United States Design Patent** (10) **Patent No.:** **US D1,055,037 S**
(45) **Date of Patent:** **** Dec. 24, 2024**

(54) **NETWORK ACCESS DEVICE**

(71) Applicant: **CenturyLink Intellectual Property LLC**, Broomfield, CO (US)

(72) Inventors: **Crystal Dawn Dowds**, Portland, OR (US); **Susan Chandler**, Parker, CO (US)

(73) Assignee: **CenturyLink Intellectual Property LLC**, Denver, CO (US)

(**) Term: **15 Years**

(21) Appl. No.: **29/867,701**

(22) Filed: **Nov. 4, 2022**

(51) **LOC (14) Cl.** **14-03**

(52) **U.S. Cl.**

USPC **D14/240**

(58) **Field of Classification Search**

USPC D14/240, 242, 357, 358, 140-140.9, 155, D14/125, 137, 139, 243

Primary Examiner — Bridget L Eland

(57) **CLAIM**

The ornamental design for network access device, substantially as shown and described.

DESCRIPTION

FIG. 1 is a perspective view of a network access device, showing our design;

FIG. 2 is a front view thereof;

FIG. 3 is back view thereof;

FIG. 4 is right side view thereof;

FIG. 5 is a left side view thereof;

FIG. 6 is a top view thereof; and,

FIG. 7 is bottom view thereof.

The broken lines showing portions of the network access device form no part of the claimed design.

1 Claim, 7 Drawing Sheets
